APPARATUS FOR EXPOSING AND DEVELOPING PHOTOGRAPHIC FILM BY THE APPLICATION OF HEAT

Charles Gordon Scott, San Jose, Calif., assignor to Kalvar
Corporation, New Orleans, La., a corporation of
Louisiana

Filed Jan. 12, 1965, Ser. No. 83,395

Term of patent 14 years

(Cl. D61—1)

The figure is a perspective view of an apparatus for exposing and developing photographic film by the application of heat, showing the top, front and right side of my new design, the essential features appearing in full lines. The left side is substantially a mirror image of the side shown, and the bottom and rear of the machine are substantially plain and unornamented.

I claim:

The ornamental design for an apparatus for exposing and developing photographic film by the application of heat, substantially as shown and described.
